[57] CLAIM

The ornamental design for a reconfigurable toy vehicle, substantially as shown and described.

DESCRIPTION

FIG. 1 is a side elevational view of a reconfigurable toy vehicle showing my new design, the side opposite being substantially a mirror image;

FIG. 2 is a front elevational view thereof;

FIG. 3 is a rear elevational view thereof;

FIG. 4 is a top plan view thereof;

FIG. 5 is a bottom plan view thereof;

FIG. 6 is a perspective view of the design shown in FIGS. 1 through 5 in a humanoid robot configuration;

FIG. 7 is a top plan view of the design shown in FIGS. 1 through 5 in an alternate reconfiguration; and,

FIG. 8 is a side elevational view thereof.

Portions of the aerial member have been omitted in FIGS. 1, 2, 3 and 8 for ease of illustration.

FIG. 1.

FIG. 2.

FIG. 3.

FIG. 4.

FIG. 5.

FIG. 6.

FIG. 7

FIG. 8.
